UNITED STATES PATENT OFFICE.

EARL RYON, OF WASHINGTON, DISTRICT OF COLUMBIA.

DESIGN FOR MOLDING.

No. 38,930.

Specification for Design.

Patented Dec. 3, 1907.

Application filed September 9, 1907. Serial No. 392,074. Term of patent 7 years.

To all whom it may concern:

Be it known that I, EARL RYON, a citizen of the United States, residing at Washington, District of Columbia, have invented a new, original, and ornamental Design for Molding, of which the following is a specification, reference being had to the accompanying drawing, in which—

The figure is a plan view of a piece of molding showing my new design.

I claim
The ornamental design for molding, as shown.

EARL RYON.
